UNITED STATES PATENT OFFICE.

CARL W. A. KOELKEBECK, OF PITTSBURGH, PENNSYLVANIA.

ADJUSTABLE GAFF.

Application filed September 29, 1921. Serial No. 504,158.

To all whom it may concern:

Be it known that I, CARL W. A. KOELKEBECK, residing at Pittsburgh, in the county of Allegheny and State of Pennsylvania, a citizen of the United States, have invented or discovered certain new and useful Improvements in Adjustable Gaffs, of which improvements the following is specification.

The invention described herein relates to 10 certain improvements in the rigging of vessels or boats having fore and aft sails. As is well known to those skilled in the art, the boom and gaff assume when the sail is hoisted, different angles to center line 15 of the hull, the angle of the gaff with such line being greater than that of the boom, so that when sailing close hauled the portion of the sail adjacent to the outer end of the gaff will be nearly parallel with the direction 20 of the wind. As the propelling effect of the wind is nearly proportional to the angle at which the wind impinges on the sail, it is evident that when sailing in any direction, except immediately before the 25 wind, a portion of the sail area will be partially ineffective.

And further, when sails are supported as at present, the pressure of the wind causes a bagging of the sail adjacent to the boom, 30 the degree of bagging being proportional to the pressure of the wind, i. e., its velocity. When such bagging occurs the foot of the sail extends from the boom nearly horizontally for a short distance, then curves upwardly. The pressure of the wind on the bagged part of the sail tends to increase the 35 submergence of the hull and as a consequence, a retardation of the rate of movement of the hull through the water.

40 The invention described herein has for its object the provision of means secured to the mast whereby the lateral movement of the gaff and its angular position relative to the center line of the hull may be regulated independent of the position of the lower end 45 of the sail. The invention is hereinafter more fully described and claimed.

In the accompanying drawings forming a part of this specification, Fig. 1 shows in 50 side elevation a portion of a mast and the upper portion of a fore and aft sail in combination with the improvement claimed herein; Fig. 2 is a top plan view of the construction shown in Fig. 1; Fig. 3 and 55 Fig. 4 are plan views illustrating modifications of the gaff spider; Figs. 5, 6, and 7

are side elevations and a plan view illustrating further modifications of the spider; Fig. 8 is a plan view of a form of spider for small sails; Figs. 9 and 10 are details of 60 said spider; Fig. 11 is an elevation showing a mast and sail combined with the form of spider shown in Fig. 8; Fig. 12 is a diagrammatic view showing the gaff and boom and illustrating the position of the sail under the present practice and the position to which the gaff and sail are preferably brought for the greatest efficiency in the practice of the invention claimed herein. 65

In the practice of the invention the sail 1 70 is of the usual or any suitable shape and is secured to the fixed mast 2, boom 3 and gaff 4 in the usual manner. The usual throat and peak halyards 5 and 6 are employed for raising the gaff to stretch the sail and the 75 boom or lower portion of the sail is shifted and held in a desired position by a sheet 3^a as is the usual practice. The trimming of fore and aft sails is dependent upon the angle between the direction of the vessel 80 and the direction of the wind, the smaller such angle the nearer must the boom be drawn to parallelism with the centerline of the vessel. As in the present no means are 85 employed except the sail itself for controlling the lateral movement of the gaff, the latter will assume a position in line or nearly in line with the direction of the wind in which position of the gaff and sail, the wind will impinge at such a small angle 90 on a large portion of the sail as to have little if any propelling effect. If, however, the gaff should be shifted toward vertical 95 parallelism with the boom, more and more of the sail will become efficient. To this end provision is made whereby the lateral position of the gaff may be changed in a manner substantially similar to that employed for adjusting the boom. A desirable means to that end consists in securing 100 to the mast at a suitable point above the normal position of the throat of the gaff, arms 7 and 8 extending at an angle to the center line of ship, and connecting these arms to the gaff by block and tackle corresponding to the sheet employed for shifting the boom. A convenient construction for securing the arms to the mast, consists of a sleeve 11 adapted to be secured around the mast and having the inner ends of the 105 arms 7 and 8 secured thereto. In the construction shown, in Figs. 1 and 2, the sleeve

110

- 11 is provided with sockets 12 for the reception of the inner ends of the arms which may be made tubular. In case it is necessary, stays 12^a may be secured to a strap 13 on the mast and caps 14 on the ends of the arms, and if desired, a spreader 15 may be interposed between the outer ends of the arms. Blocks 9 and 10 are attached to the arms and gaff respectively, and the sheets 10 passing through these blocks extend down adjacent to the mast to the deck. When the improvement is used in connection with small sails, the arms 7 and 8 may be made integral with the sleeve 11^a, as shown in 15 Figs. 3 and 4 and the sleeve may be made integral and slipped over the top of the mast, or may be made in sections as shown in Fig. 4 and secured around the mast by bolts and nuts.
- 20 In Figs. 5, 6, and 7 is shown a construction in which the sleeve 11^b is formed in sections adapted to be secured together, and the arms 7 and 8 formed integral with one of the sections. At the lower ends the sleeves are provided with lugs 16 having eyes and to these lugs the upper ends of the shrouds 17 may be secured. A lug 18 may be formed at the lower end of one of the sections and to the lug may be connected the upper block of the 25 throat halyards, and the inner block of the peak halyards may be secured to a vertical rib 19 on the sleeve section. The other sleeve section may be formed with a rib 20 to which may be connected stays 21.
- 30 In Figs. 8, 9, 10, and 11 is shown a construction which is suitable for sails for small sloops, cat-boats, etc. In this construction the arms 7^a and 8^a are formed integral with the sleeve 11^a and the outer ends of the arm 35 are connected by a curved member 22 provided with a plurality of lugs 23 spaced a distance a little greater than the transverse dimensions of the gaff. When using this construction, the gaff or at least the outer 40 end of the gaff is lowered, when the sail is to be shifted, and when the gaff in its lateral movement, reaches the desired position, it is raised so as to pass between adjacent lugs.
- 45 It is characteristic of the invention that provision is made for laterally shifting the gaff as well as the boom so that substantially the entire area of the sail will be presented at such an angle to the wind, even when the vessel is close hauled, as to be effective in 50 moving the vessel. It is believed that by shifting the gaff forward of the boom, or to a position more nearly parallel with the center line of the vessel as shown in Fig. 12, the wind will act more efficiently on the entire area of the sail.
- 55 When the gaff is allowed entire freedom of movement as in the present practice, there will be a bagging of the sail adjacent to the 60 foot, as shown in dotted lines in Fig. 12, but

by shifting the gaff to a position in advance of the boom as shown in full lines in Fig. 12 the upper portion of the sail will be in such a position that the wind will exert an upward pressure and thereby not only eliminate the bagging at the foot of the sail but tend to lift the vessel to a greater or less degree. 70

It is characteristic of the improvements described and claimed herein that the means 75 employed for shifting or determining the position of the gaff laterally are fixed to the mast.

No claim is made herein broadly to the provision of means other than the usual 80 for determining the angular position of the gaff to the direction of the wind, as such improvements form the subject matter of a patent No. 1,438,246, granted Dec. 12, 1922.

I claim herein as my invention:

1. A vessel having in combination therewith a non-rotatable mast, a gaff, a sail depending from the gaff, halyards for raising the gaff, arms secured to the mast and extending from the mast in directions at angles 90 to the center line of the vessel, and means carried by the arms and adapted to engage and maintain the gaff in any desired position relative to the center line of the vessel.

2. A vessel having in combination therewith a non-rotatable mast, a gaff, a sail extending from the gaff, halyards for raising the gaff, arms secured to the mast and extending from the mast in directions at right angles to the center line of the vessel and means extending from the arms to the gaff for shifting the latter in directions transversely of the vessel. 100

3. A vessel having in combination therewith a non-rotatable mast, a gaff, a sail 105 depending from the gaff, halyards for raising the gaff, a sleeve secured to the mast, blocks for the halyards connected to the sleeve, arms extending from the sleeve in directions at angles to the center line of the 110 vessel and means carried by the arms and adapted to engage and maintain the gaff in any desired position relative to the center line of the vessel.

4. A vessel having in combination therewith a nonrotatable mast, a gaff, a sail depending from the gaff, halyards for raising the gaff, a sleeve secured to the mast, shrouds having their upper ends secured to the sleeve, blocks for the halyards connected to the 120 sleeve, arms extending from the sleeve in directions at angles to the center line of the vessel and means carried by the arms and adapted to engage and maintain the gaff in any desired position relative to the center 125 line of the vessel.

In testimony whereof I have hereunto set my hand.

CARL W. A. KOELKEBECK.
